UNITED STATES PATENT OFFICE.

ALBERT PARADIS, OF PHILADELPHIA, PENNSYLVANIA, ASSIGNOR TO SAMUEL STERNBERGER COMPANY, A CORPORATION OF PENNSYLVANIA.

SHIRT-CUFF.

1,089,782.

Specification of Letters Patent. Patented Mar. 10, 1914.

Application filed March 7, 1913. Serial No. 752,544.

To all whom it may concern:

Be it known that I, ALBERT PARADIS, a citizen of the United States, residing in the city and county of Philadelphia, State of Pennsylvania, have invented a new and useful Shirt-Cuff, of which the following is a specification.

My invention relates to a shirt cuff, adapted to be folded on a transverse line, so as to present a clean edge and a clean outer surface, and it consists of a cuff that may be folded as above stated, and while it is provided with the usual holes for cuff buttons, it is furthermore provided with means for connecting what may be termed the back of the cuff so as to prevent bulging or shifting of the outer portion of the cuff at said back.

The invention is satisfactorily illustrated in the accompanying drawing, but the important instrumentalities thereof may be varied, and so it is to be understood that the invention is not limited to the specific arrangement and organization shown and described.

Figure 1 represents a plan view of a cuff in extended position embodying my invention. Figs. 2 and 3 represent perspective views thereof on an enlarged scale, the members of the cuffs being in different positions in the two figures. Fig. 4 represents a longitudinal section on line $x-x$ Fig. 2.

Similar numerals of reference indicate corresponding parts in the figures.

Referring to the drawings:—1 designates a cuff which is stitched to the sleeve of a shirt and provided with registering buttonholes 2 therein near the front, and with registering buttonholes 3 therein near the rear, it being noticed that the cuff is adapted to be folded say on the transversely extending median line 4 whereby the buttonholes 2 and 3 of each side may register to receive a cuff button or stud as heretofore known, it being noticed also that the front portion or section 5 of the cuff comprising the cuff proper may be folded over the rear portion or section 6 thereof as the wristband of the shirtsleeve, as in Fig. 2, or beneath the same, as in Fig. 3.

When the parts are in position as in Fig. 2, and the front-folded edge 7 of the cuff has become soiled as may also the outer surface

of the portion 5, the cuff buttons are removed and the part 5 is folded within the part 6 when the front folded edge 8 of the cuff is presented clean, as is also the exterior of the portion 6. Then the cuff button is re-applied and the cuff presents the appearance as shown in Fig. 3.

In order to prevent shifting of the cuff at what may be termed its back 9 either forwardly or rearwardly which would make the edges 7 and 8 irregular, and distort the appearance of the cuff especially at said edges, I couple the portions 5 and 6 of the cuff adjacent to the place of connection with the sleeve 10 of the shirt. This is accomplished by forming a buttonhole 11 in the front of the portion 5 of the cuff and one 12 in the rear of the portion 6, so that when the portion 5 is turned over or under the portion 6, said buttonholes 5 and 6 register. A stud 13 or other buttoning device is then inserted in said holes 11 and 12, whereby the portions 5 and 6 are buttoned together, and so prevented from shifting or riding on each other and displaced or distorted as hereinbefore referred to and to which attention is particularly directed, as also to the fact that the holes 11 and 12, and the stud 13 will be concealed by the sleeve of the coat of the wearer and so will not objectionably present themselves during the wearing of the cuff as doubled or folded.

Having thus described my invention what I claim as new and desire to secure by Letters Patent, is:—

In a shirt, a combined wrist band and a reversible cuff composed of a wrist band section proper, and a cuff section proper, said sections being joined at their front by a fold of the material of the two sections, said sections having registering buttonholes near their side ends for the reception of fastenings for controlling said ends, and auxiliary registering buttonholes in the back of the sections rearward of the front fold for the reception of fastenings for controlling said backs at said fold.

ALBERT PARADIS.
